UNITED STATES PATENT OFFICE.

RUDOLPH W. BETTOLI, OF SAN RAFAEL, CALIFORNIA, ASSIGNOR OF ONE-THIRD
TO HAZEL M. PEATTIE, OF SAN RAFAEL, CALIFORNIA, AND ONE-THIRD TO J. E.
TRABUCCO, OF SAN FRANCISCO, CALIFORNIA.

DESIGN FOR A NURSING BOTTLE.

Application filed October 3, 1927. Serial No. 23,598. Term of patent 7 years.

To all whom it may concern:

Be it known that I, RUDOLPH W. BETTOLI, a citizen of the United States, residing in the city of San Rafael, county of Marin, and State of California, have invented a new, original, and ornamental Design for a Nursing Bottle, of which the following is a specification, reference being had to the accompanying drawing, forming a part thereof.

Fig. 1 is a front view of a nursing bottle showing my new design; and

Fig. 2 is a side view of the same.

I claim:

The ornamental design for a nursing bottle as shown.

RUDOLPH W. BETTOLI.
